UNITED STATES PATENT OFFICE.

WILLIAM E. BERTRAM, OF BROOKLYN, NEW YORK, ASSIGNOR TO INTERNATIONAL TYPESETTING MACHINE COMPANY, OF NEW YORK, N. Y., A CORPORATION OF NEW YORK.

LINOTYPE-MACHINE.

1,168,244.

Specification of Letters Patent. Patented Jan. 11, 1916.

Application filed November 30, 1912, Serial No. 734,325. Renewed August 17, 1915. Serial No. 46,016.

To all whom it may concern:

Be it known that I, WILLIAM E. BERTRAM, a citizen of the United States, residing at Brooklyn, in the county of Kings and State 5 of New York, have invented new and useful Improvements in Linotype-Machines, of which the following is a specification.

This invention relates to improvements in linotype machines in which matrices having 10 two characters in each are stored in a magazine and drawn therefrom at the will of the operator by means of the keyboard and assembled in a line on either or both of two different levels, and the line thus assembled 15 is delivered to an elevator known as the first elevator which carries the line to a casting position, and, after the casting operation, lifts the line to a position where the line may be transferred to the second elevator, which 20 in turn carries it into the distributing mechanism. In this case it is customary to provide a stop which will prevent the first elevator from reaching its uppermost position, thereby avoiding those movements whereby 25 the matrices are brought to a common level. It frequently occurs that the operator in setting the stop whereby this action is prevented, fails to lock the transfer mechanism, in which event its operation is very destructive 30 of the matrices which are on different levels.

The object of this invention is to provide an automatic latch operated by the action 35 of the first elevator which will lock the transfer slides and prevent the discharge of the line in case the operator failed to manipulate and lock it by hand, thereby insuring certainty in the operation of the machine.

To these and other ends, the invention 40 consists in certain improvements, and combinations and arrangements of parts, all as will be hereinafter more fully described, the novel features of the invention being pointed 45 out particularly in the claims at the end of the specification.

In the accompanying drawings:—Figure 1 is a front elevation of a portion of a linotype machine showing the first elevator and 50 the related parts with the present invention applied thereto; Fig. 2 shows, on an enlarged scale, the matrix transfer channel and slide, an automatic latch embodying the present invention being shown in full lines

in coöperative relation with the transfer 55 slide, and the broken lines indicating the uppermost position of the first elevator and the disengaged position of the latch; Fig. 3 is a perspective view showing in detail the matrix transfer slide and the coöperative 60 latch; Fig. 4 is a side elevation showing the first elevator in section and illustrating the stop for limiting the upward movement of the first elevator; Fig. 5 is a view of the lower portion of Fig. 4 as it appears from 65 the right, showing the limiting stop for the first elevator.

Similar parts are designated by the same reference characters in the several views.

The invention in the present instance is 70 shown in connection with a linotype machine of the usual and well known construction, 1 designating the first elevator carrying the usual jaws 2, and 3 designating the vise, the jaws of which operate to clamp a 75 composed line of matrices, the first elevator receiving a composed line of matrices from the channel 4 forming a part of the matrix-assembling mechanism while in an intermediate position, and when the 80 first elevator moves downwardly into its lower position, it conveys the assembled line of matrices to a position between the jaws of the vise 3 which operates in the usual way to clamp the line before the mold on 85 the mold wheel 5.

In the usual operation of linotype machines, the first elevator rises and lifts the line of matrices, after a cast has been made therefrom, up to a position where the line 90 of matrices is transferred to the distributing mechanism preparatory to the return of the matrices to their respective cells or channels of the magazine, the transfer mechanism embodying a transfer channel 6, and a reciprocal transfer slide 7, the latter being mounted to operate between the jaws 2 of the first elevator and to thereby sweep the line of matrices from this elevator and into the transfer channel 6. In the present in- 95 stance, as shown, the first elevator is adapted to contain matrices assembled at different levels, a movable rail 8 serving to support the matrices at the upper level, and this rail may be retracted by any suitable or well 100 known means at the moment the first elevator reaches substantially the limit of its upward movement, whereby all of the mat-

100

105

rices in the line will be positioned at the same level immediately before the slide 7 operates to transfer the line of matrices from the first elevator to the distributing mechanism.

According to the present invention, the transfer slide 7 is provided with a notch 9, and a latch 10 is provided, this latch being pivoted at 11 to a suitable stationary part 10 of the machine and is provided with a dog or projection 12 which is adapted to engage in the notch 9 of the transfer slide while the latter is in its retracted position and thereby prevent operation of the slide to 15 transfer the line of matrices from the first elevator to the distributing mechanism. This latch is provided with a trip 13 which is in the line of movement of the rear jaw of the first elevator. This latch which may operate 20 by gravity automatically engages with and locks the transfer slide at each time the slide reaches its retracted position, and when the machine is operated in the usual manner to distribute the matrices after each cast 25 therefrom, the first elevator upon reaching the limit of its upward movement will abut against the trip 13 of the latch 10, thus transferring movement from the elevator to the latch and causing the dog 12 of the latch 30 to disengage from the notch 9 of the slide, thereby unlocking the slide and permitting the latter to operate and perform its function of transferring the line of matrices from the first elevator to the distributing mechanism. The final upward movement of 35 the first elevator also serves to retract the rail 8 and thereby permit such matrices as were assembled at the upper level to drop to the same level with the lower matrices. 40 However, when it is desirable to repeat the casting operation using the same line of matrices, the upward movement of the first elevator is limited or arrested so as to avoid retraction of the rail 8, thereby maintaining 45 the matrices in the line in properly assembled condition and preventing tripping of the latch 10, whereby the transfer slide 7 will remain locked. A limiting stop 14 is provided in the present instance which is 50 pivoted to a suitable portion of the stationary frame at 15, and an abutment, preferably in the form of a set-screw 16, is provided on the first elevator which, when the stop 14 is set in one position, will come 55 against the stop and thereby limit the upward movement of the first elevator, preventing restoring of the matrices to a common level, and maintaining the transfer slide 7 in locked condition, such relation of the parts being shown in Fig. 4. The thickness of the stop 14 corresponds to the distance at which the first elevator will be arrested below its uppermost position. When 60 it is desirable to resume the usual operation of the machine, that is to say, to cause each 65

line of matrices to be distributed after a single cast has been made therefrom, it is only necessary to move the stop 14 into a position where it will clear the abutment 16 on the first elevator, the latter then being 70 permitted to reach its uppermost position where the rail 8 will be retracted and the bar 17 will operate to bring all the matrices in the line to a common level, and the latch 10 will be tripped to permit the usual operation 75 of the slide 7 to transfer the line of matrices to the distributing mechanism.

I claim as my invention:—

1. In a linotype machine, the combination of a matrix-carrying elevator, a transfer slide adapted to coöperate therewith, a latch coöperative automatically with the slide to lock the same in retracted position and releasable by the elevator when the latter reaches substantially its uppermost position, and a limiting stop adapted when in its operative position to arrest the movement of the elevator and thereby avoid releasing of the latch. 80

2. In a typographical machine, the combination of a matrix carrier to transport the matrices to and from the mold, a receiving device, means for transferring the matrices from the carrier to the receiving device, and locking devices controlled by the matrix carrier for preventing the operation of said transfer means unless the parts are in a proper registration with each other. 85

3. In a typographical machine, the combination of a matrix carrier to transport the matrices from one position to another in the machine after casting for distribution, a receiving device, means for transferring the matrices from the carrier to the receiving device, and locking devices controlled by the matrix carrier for preventing the operation of the transfer means unless said parts are in proper operative relation to each other. 100

4. In a typographical machine, the combination of the elevator to present the matrices for casting and movable vertically to deliver them for distribution, means for transferring the matrices from the elevator when in its uppermost position, and locking means controlled by the elevator to prevent the operation of said transfer means when the elevator fails to rise to the proper extent. 110

5. In a typographical machine, the combination of the elevator to present the matrices for casting and movable vertically to deliver them for distribution, means for transferring the matrices from the elevator when in its uppermost position, and locking devices to prevent the operation of said transfer means, the said devices adapted to be released by the elevator when it reaches the said position. 120

6. In a typographical machine, the combination of a matrix carrier to transport the matrices from one position to another in the 125
